UNITED STATES PATENT OFFICE.

WILLIAM ANDREW HYLE, OF BUFFALO, NEW YORK, ASSIGNOR TO PETER E.
MACDONALD, OF TORONTO, CANADA.

VISE.

1,009,970.

Specification of Letters Patent. Patented Nov. 28, 1911.

Application filed November 25, 1910. Serial No. 594,022.

To all whom it may concern:

Be it known that I, WILLIAM ANDREW HYLE, a citizen of the United States, and resident of Buffalo, in the county of Erie 5 and State of New York, have invented new and useful Improvements in Vises, of which the following is a specification.

This invention relates to a vise which is used more particularly for holding pipes 10 but which may also be used for other purposes.

One of the objects of this invention is the provision of simple and efficient means whereby the principal part of the adjustment of the vise may be effected quickly and 15 only the final tightening effected slowly.

This invention has the further object to render the movement of the parts while opening and closing the vise easy and to so 20 construct the parts that the vise is very strong, that worn parts can be readily replaced and the vise can be produced at low cost.

In the accompanying drawings consisting 25 of 2 sheets: Figure 1 is a horizontal section in line 1—1, Fig. 2. Fig. 2 is an end elevation of the vise. Fig. 3 is a vertical longitudinal section in line 3—3, Fig. 1. Figs. 4, 5 and 6 are vertical transverse sections 30 in the correspondingly numbered lines in Fig. 3.

Similar letters of reference indicate corresponding parts throughout the several views.

35 A represents the base of the vise which may be secured to a work bench or other support in any suitable manner. At its front and rear ends this base is provided with two upright front and rear standards 40 or posts B, C which are fixed on the base and preferably cast integrally therewith. Between the two standards the base is provided with a longitudinal slot D which is undercut so as to form downwardly facing 45 shoulders d, d on opposite sides of the slot, as shown in Figs. 3, 4 and 6. To the rear standard are secured the two widely separated sections E, E of a rear fixed gripping jaw which are adapted to engage with the 50 rear side of the pipe and widely separated points and which are detachably secured to opposite sides of the rear standard by bolts e, as shown, or by any other suitable means. Arranged in front of the space between the

rear fixed jaw sections are two narrowly 55 spaced sections F, F of a front movable gripping jaw which are adapted to bear against the front side of the pipe at two points arranged comparatively close together and out of line with the bearing 60 points of the rear jaw sections. It will thus be noted that the pipe by this means is gripped at four different places whereby the same is positively held against turning while a thread is being cut on the same or other 65 work is being performed thereon which requires the pipe to be held firmly.

The front jaw sections are secured by bolts g or otherwise to opposite sides of an upright longitudinally movable slide G 70 which projects at its lower end downwardly through the guide slot D and moves lengthwise therein for opening and closing the vise. The lower ends of the front jaw sections are arranged above the base on opposite sides of the slot D and thereby prevent downward movement of the front jaw and slide. Upward movement of these parts is prevented by a cross head h arranged at the lower end of the slide G and engaging at its 80 opposite ends with the shoulders d, d of the slot D.

In order to cause the front jaw and slide to move freely without liability of becoming cramped or bound, rolling members or 85 bearings are interposed between the lower ends of the front jaw sections and the base. These rolling members preferably consist of a plurality of balls i arranged in recesses i¹ in the lower ends of the front jaw sections 90 and engaging with longitudinal rim ways on the upper side of the base on opposite sides of the slot D, as shown in Figs. 2 and 6.

The forward and backward movement of the front jaw and slide relatively to the rear 95 jaw may be effected by various means but preferably a horizontal screw J which is operatively connected at its front end with the front jaw and slide and works in a screw nut in the front standard. The preferred 100 means for connecting the screw with the slide and front jaw comprises a spherical knuckle L connected with the rear end of the screw by a contracted neck l and seated in a spherical socket in the slide and front 105 jaw sections. As shown, this socket is formed by means of a notch arranged in the front edge of the slide and consisting of a narrow

or contracted outer part m and an enlarged inner part m^1 and two concave recesses n formed on the inner sides of the front jaw sections in line with the enlarged inner part m^1 of said notch.

- 5 In the assembled condition of the parts the neck l of the screw is arranged in the contracted part m of the notch and the spherical knuckle engages centrally between its laterally opposite sides with the enlarged part m^1 of the notch while its opposite sides engage with the recesses n of the front jaw sections, thereby forming a swiveling connection between the screw and movable jaws 10 which permits of freely adjusting the latter without liability of binding and still keeping the cost of manufacture and the capacity of being repaired within practical bounds.

At its front end the screw is provided 20 with a handle o for turning the same which handle may be of any suitable construction, the same being shown in the drawings, for example, in the form of a cross bar.

In its preferred form the adjusting screw 25 nut which co-operates with the screw, as shown in Figs. 1 2, 3 and 5, is constructed of two cylindrical sections p , p^1 which are arranged in a cylindrical socket P in the front standard and which have their opposing ends constructed to form an opening which is internally threaded and in line with openings q , q^1 in the front standard on opposite sides of the screw nut. The adjusting screw passes through the adjusting nut 30 and the adjacent openings q of the front standard. Upon turning the screw in one direction or the other while the nut sections are both engaged therewith the front jaw will be slowly moved toward or from 35 the rear jaw accordingly. When it is desired to move the front jaw quickly toward or from the rear jaw the sections of the adjusting nut are separated and the adjusting screw is disengaged therefrom, thereby permitting the adjusting screw to be moved 40 lengthwise through the adjusting nut without turning the same and thus enabling the main part of the adjustment of the vise to be effected rapidly. After the parts have 45 been shifted approximately into the position for gripping a pipe the sections of the adjusting nut and the adjusting screw are again engaged and the final tightening of the jaws against the pipe is effected by turning 50 the adjusting screw in the screw nut. By this means the operation of adjusting the vise pipes is materially facilitated and cost of doing the work reduced accordingly.

The lower adjusting screw nut section p^1 55 is preferably secured in the front standard by a transverse pin r and the upper section p is movable vertically toward and from the lower section but is held against turning by means of a pin s projecting laterally 60 from the upper nut section through a ver-

tical slot s^1 in one side of the front standard. At its upper end the upper nut section is provided with a handle or knob s^2 for manipulating the same.

Various means may be employed for holding the upper section p in its operative or inoperative position, the means for this purpose shown in the drawings consisting of a leaf-shaped locking spring T secured at one end to the outer side of the front standard and provided at its other end with two openings t , t^1 which are adapted to receive the pin s of the upper nut section. When the upper nut section is depressed into its operative position the pin s engages with the lower opening t^1 of the locking spring T , thereby holding the adjusting screw nut sections and screw in engagement with each other. Upon raising the upper screw nut section and engaging its pin s with the upper opening t of the locking spring this nut section will be held in its inoperative position.

By splitting the screw nut the same may be separated and the adjusting screw detached therefrom and the movable jaw 90 quickly shifted while the fine adjustment and tightening of the jaws is effected when the adjusting screw is engaged by the screw nut sections. The adjusting screw can be readily lifted out of engagement from the 95 lower fixed section of the screw nut owing to the pivotal connection between this screw and the slide which carries the movable jaw.

The screw nut sections p , p^1 are constructed from a cylindrical block which is 100 first bored transversely, then internally threaded in this bore and then divided transversely through this bore. The opening or socket P in the standard B is of the same diameter as the screw nut sections p , p^1 105 so that the latter fit snugly in this socket. This manner of constructing the screw nut sections and mounting the same in the standard B is very simple, reliable and efficient and can be produced at low cost. 110

I claim as my invention:

1. A vise comprising a base having two standards, a stationary jaw arranged on one of said standards, a divided screw nut mounted on the other standard and composed of a fixed section and a movable section movable toward and from the fixed section, a slide guided on the base between said standards, a movable jaw mounted on said slide, and an adjusting screw pivotally connected with said slide and having its threads engaged on opposite sides by the threads of said screw nut sections. 115

2. A vise comprising a base having two standards and an undercut slot between said standards, a fixed jaw arranged on one of said standards, a central slide having a head arranged in said undercut slot, two jaw sections secured to opposite sides of the slide, said slide being provided with a notch in its 120

outer edge which has a narrow outer part and an enlarged inner part and said movable jaw sections having their inner sides provided with recesses in line with the enlarged part of the notch in said slide, said recesses and enlargement of the notch forming a spherical socket, an adjusting screw having a spherical head which is seated in said socket, and a split screw nut mounted 10 on the other standard and having a fixed section secured to its standard and a vertically movable section guided on its standard.

3. A vise comprising a base having two fixed standards one of which is hollow, a 15 screw nut arranged in the hollow standard and composed of a fixed section and a movable section, a pin arranged on the movable nut section and projecting through a slot in the respective standard, a spring secured 20 to the last mentioned standard and engaging with said pin, a screw engaging with the screw nut, a movable jaw connected with the screw, and a fixed jaw connected with the other standard.

4. A vise comprising a base having two 25 standards, one of which is provided with a cylindrical opening forming a hollow standard, a fixed jaw secured to the other standard, a divided cylindrical block having the opposing ends of its sections constructed to 30 form the two parts of a screw nut, the sections of said block being arranged in said opening of said hollow standard and movable one relatively to the other, a side guided on the base between said standards, 35 a jaw mounted on the slide, and an adjusting screw connected with said slide and having its threads engaged by the threads of said screw nut sections.

Witness my hand this 17th day of November, 1910.

WILLIAM ANDREW HYLE.
